UNITED STATES PATENT OFFICE.

LOUIS H. THULLEN, OF EDGEWOOD PARK, PENNSYLVANIA, ASSIGNOR
TO THE UNION SWITCH AND SIGNAL COMPANY, OF SWISSVALE,
PENNSYLVANIA, A CORPORATION OF PENNSYLVANIA.

RAILWAY-SIGNAL-OPERATING MECHANISM.

No. 821,899.

Specification of Letters Patent.

Patented May 29, 1906.

Application filed March 24, 1906. Serial No. 307,833.

To all whom it may concern:

Be it known that I, LOUIS H. THULLEN, a citizen of the United States, residing at Edgewood Park, in the county of Allegheny and State of Pennsylvania, have invented certain new and useful Improvements in Railway-Signal-Operating Mechanisms, of which the following is a specification.

My invention relates to mechanisms for operating railway-signals, and which are designed for use more particularly in connection with that class of signals known in the art as "semaphore-signals." These signals are generally pivotally supported on uprights or posts at predetermined intervals throughout the signaling system and usually comprise a signal arm or blade and a spectacle having openings therein in which are arranged different-colored lenses designed for illumination to give indication by night, the whole being so disposed relatively with each other that under certain conditions the spectacle will act as a weight or counterpoise and move the signal-arm to one of its positions of indication, usually to a horizontal position, indicating "danger," while appropriate mechanism, in which are included the important features of my invention, will move the signal arm or blade to assume an inclined position indicating "safety." These movements of the signal arm or blade, and especially at the final completion of its strokes, cause considerable shock and strain on the various parts and connections, which are necessarily heavy in their construction. This has usually been overcome, or at least considerably minimized, by the addition of buffers which have generally been permanently connected to the operating mechanism in such manner as to act as a cushion to take up the impact of the parts at the completion of the stroke of the signal.

The buffers at present in use generally comprise a dash-pot and plunger, the latter being permanently connected to some part of the signal-operating mechanism and arranged to act as a cushion only when the signal arm or blade moves to the horizontal position of "danger;" but, owing to the positive and permanent connection between the buffer or cushion device and the operating mechanism, before mentioned, it has been ob-

served that the plungers at times become inoperative, or at least uncertain in their action, due to their tendency to stick in the dash-pots, which render the operation of the signals more or less doubtful. Obviously, therefore, a permanent connection between the signal-operating mechanism and the buffer or cushion device is undesirable and is likewise detrimental to the positive and successful operation of the signal arm or blade for the reasons stated. To overcome these objections and to provide for the positive operation of the signal blade or arm under all conditions are among the important objects of my invention, which may be said to comprise a buffer or cushion device in combination with a signal-operating mechanism and a movable part connected to the signal arm or blade and adapted to engage the buffer or cushion device after a partial movement of the signal arm or blade has been effected in either direction.

I will describe a buffer or cushion device embodying my invention, illustrating its application to a signal-operating mechanism, and then point out the novel features thereof in claims.

In the accompanying drawings, Figure 1 represents a sectional elevation of a signal-operating mechanism and signal having a buffer or cushion device embodying my invention applied thereto. This view illustrates what is known in the art as a "high signal," and the signal arm or blade is shown separated therefrom for purposes of convenience. Fig. 2 is a plan view thereof, the signal arm or blade being omitted. Fig. 3 is a sectional elevation of what is known in the art as a "dwarf signal," having a buffer or cushion device embodying my invention applied thereto. Fig. 4 is a similar view taken on the line 4-4 of Fig. 3, showing the semaphore or signal arm in dotted lines.

Similar reference characters designate corresponding parts in all the figures of the drawings.

Referring to said drawings, A designates an electromagnetic device for controlling the operation of the signal arm or blade B, which is moved from one position to another through the medium of a movable part C and connecting-rod D. The electromagnetic device may

- be of any desired form or construction, and for purposes of illustration I have shown it in the form of a solenoid having the usual core *a*, the lower end of which is connected to the movable member *C*, which, as here shown, comprises a lever pivotally supported in suitable bearings and adapted to rise and fall with the core *a*, as will be obvious. The connecting-rod *D* is pivoted at one end to the lever *C* and at its other end to the signal arm or blade, as shown, so that an upward movement of said lever will cause the rod *D* to move the signal arm or blade to an inclined position to indicate "safety," while upon a return or downward movement of the lever the signal arm or blade will move to a horizontal position indicating "danger." This position of the parts is shown in the drawings and is well understood in the art.
- 20 The lever or movable member *C* travels in the path of my improved buffer or cushioning device, which is so arranged relatively with the lever as to permit the latter to have a partial and free movement in both directions before it engages the cushion or buffer, thereby positively effecting a movement of the signal arm or blade and insuring the proper performance of its functions.
- The buffer or cushion device as here shown
- 30 comprises two cylinders *E* and *F* and coacting plungers *e* and *f*, disposed in such manner with respect to the lever *C* that as the latter moves in one direction or the other it will alternately engage the plungers and take
- 35 up the impact due to the rise and fall of the signal-arm and its connections. The cylinder *E* is preferably secured to a base-plate *G*, which may form a common support for the solenoid or other electromagnetic device and
- 40 movable member *C*, as shown, and its plunger *e* may be provided with resilient means for moving it into a position to meet the movable member as the latter travels toward it during the operation of the signal arm or
- 45 blade, thereby establishing a spring-cushion to minimize the shock or impact of said movable member and connected parts. This is accomplished, preferably, by the use of a spiral spring *H*, one end of which rests on the
- 50 base-plate *G* and its other end against the extremity of an opening *h*, provided for the purpose in the plunger *e*.
- The plunger *f* may be similarly constructed to that just described, and a spring may also
- 55 be employed to move it into position to meet the movable member as it travels toward it; but I prefer to arrange said plunger so as to fall by gravity, as shown, and to have the air alone, which is compressed in the cylinder *E*
- 60 behind the plunger as the latter moves in the cylinder, act as a cushion to take up the impact of the lever and its connections as they move in an opposite direction.

The buffers are preferably arranged in vertical order, as shown, to meet the require-

ments of a vertical stroke of the movable member *C* and rod *D* and are so disposed relatively as to provide a space between their respective plungers *e* and *f* in order that the lever *C* may have a partial and unobstructed movement before it contacts with either of said plungers. Thus the gradual momentum of the lever will when it encounters either of the plungers serve to release them should they stick in the cylinder, and thereby insure the positive operation of the signal arm or blade.

The construction shown in Figs. 2 and 3 is similar in many respects to that just described, the difference existing merely in the connections between the signal arm or blade and the electromagnetic device. It will be seen that the lever *C* is dispensed with and a connecting-rod *D'* is secured directly to the core *a*, its upper extremity being guided in a suitable keeper *d*, arranged in a housing which preferably incloses the operating mechanism. The signal arm or blade is mounted on a crank-shaft *J*, and the crank-arms *j j* are each provided with an elongated groove *j' j'*, in which lateral extensions on the shaft *J* move. These extensions may comprise a pin *j²*, projecting through the connecting-rod *D'* sufficiently far to receive thereon rollers *j³ j⁴*, which when said rod rises under the influence of current in the magnets of the solenoid will travel in the grooves *j' j'*, and thus remove any strain which would otherwise be exerted on the rod *D'*. The core *a* in this construction projects below the winding of the electromagnetic device *A* and engages the plunger *e* of the buffer or cushion device *E*, and the extremity of the rod *D'* engages the plunger *f* of the buffer or cushion device *F* when the signal arm or blade moves to its different positions.

In the operation of my invention and when the system of signaling is that of the normally clear the magnets of the electromagnetic device are magnetized and its core or armature *a* attracted to the poles thereof, so that the movable member will be lifted to the dotted-line position shown in Fig. 4, thereby lifting the rod *D'* and moving the signal arm or blade *B* to its inclined position, indicating "safety." When, however, the magnets of the electromagnetic device are demagnetized, which is their condition illustrated in the drawings, and due generally to short-circuiting or opening of a circuit leading from a battery or other source of current-supply included in the circuit for controlling the operation of the signaling mechanism, the spectacle by its weight, combined with that of its connections, will cause the signal blade or arm to move to the horizontal position of "danger," during which movement the movable member will engage the buffer or cushion device *E*, as previously described.

Having thus described my invention, what

I claim, and desire to secure by Letters Patent, is as follows:

1. The combination with a mechanism for operating a railway-signal comprising an electromagnetic device, of a buffer or cushion device, a movable part controlled by said electromagnetic device, and adapted to engage the said buffer or cushion device upon a movement of said signal in either direction, and a connection between said movable part and the signal. 45
2. The combination with a mechanism for operating a railway-signal comprising an electromagnetic device, of a buffer or cushion device, a movable part controlled by said electromagnetic device and adapted to engage said buffer or cushion device after a partial movement of said signal has been effected in either direction, and a connection between said movable part and the signal. 50
3. The combination with a mechanism for operating a railway-signal comprising an electromagnetic device, of a buffer or cushion device comprising two cylinders and coacting plungers, a movable part adapted to alternately engage the plungers upon a movement of said signal in either direction, and a connection between said movable part and the signal. 55
4. The combination with a mechanism for operating a railway-signal comprising an electromagnetic device, of a buffer or cushion device comprising two cylinders and coacting plungers separated from each other to provide a space therebetween, a movable part adapted to travel between the respective plungers and to engage them after a partial movement of the signal has been effected in either direction, and a connection between the movable part and the signal. 60
5. The combination with a mechanism for operating a railway-signal, comprising an electromagnetic device, of a buffer or cushion device, a movable part controlled by said electromagnetic device and adapted to engage said buffer or cushion device after a partial movement of the signal in either direction has been effected, and a connection between the movable part and the signal. 65
6. The combination with a mechanism for operating a railway-signal, comprising an electromagnetic device, of a buffer or cushion device comprising two cylinders and coacting plungers separated from each other to provide a space therebetween, a resilient device so disposed with relation to one or both of said plungers as to move them in one direction, a movable part adapted to alternately engage the plungers only after a partial movement of the signal in either direction has been effected, and a connection between said movable part and the signal. 70
7. The combination with a mechanism for operating a railway-signal, comprising an electromagnetic device, of a buffer or cushion device comprising two cylinders and coacting plungers separated from each other to provide a space therebetween, a spring so disposed with relation to one of said plungers as to move it in one direction, a movable part comprising a lever adapted to have a free and unobstructed movement between the plungers and to alternately engage them only after a partial movement of the signal in either direction has been effected, and a connection between the movable part and the signal. 75

In testimony whereof I have signed my name to this specification in the presence of two subscribed witnesses.

LOUIS H. THULLEN.
